200,489

DETACHABLE HANDLE FOR SAUCEPANS OR THE LIKE

Austin H. Munson, Arlington Heights, and Raymond E. Paddock, Prospect Heights, Ill., assignors to Ekco Products Company, Chicago, Ill., a corporation of Delaware

Filed June 19, 1964, Ser. No. 80,477

Term of patent 14 years

(Cl. D44—29)

FIG. 1

FIG. 2

FIG. 3

FIG. 4

FIG. 1 is a side elevational view of a detachable handle for saucepans or the like, showing our new design.

FIG. 2 is a top plan view thereof.

FIG. 3 is a bottom plan view thereof.

FIG. 4 is a front end view thereof.

We claim:

The ornamental design for a detachable handle for saucepans or the like, as shown.
